[57] ABSTRACT

[51] Int. Cl. B61f 5/16, F16c 17/04, F16c 41/00

The present invention involves a wear ring which fits in the recess of a truck bolster center plate to protect the inner annular wall of the recess. The annular wall has a double taper which first tapers outward a distance from top to bottom and then tapers inward a part of the distance. The ring has a double tapered outer surface from top to bottom which is complementary to the interior wall of the recess.

FIG. 1

FIG. 2

FIG. 3

CENTER PLATE VERTICAL WEAR RING

Vertical ring wear liners presently used in truck bolster center bowls have parallel and vertical walls which are generally secured by a circumferential weld at the top inside and by a perpendicular weld at the ends.

However, the male car body bolster center plate rocks in the truck bolster center bowl laterally and longitudinally in such a manner that a vertically downwardly force is imposed on the vertical ring wear liner on the low side and a vertically upwardly force is imposed on the diametrically opposite high side. These loads contribute to weld cracking and subsequently, the vertical ring wear liner tends to rise in the truck bolster and works out of the female recess which leads to rapid wear of the truck bolster rim and cracking of the rim and/or ring. The result is high destructive forces which are imposed on the truck and car body bolsters due to the uncontrolled action of the center plate interfaces.

Accordingly, it is among the objects of the invention to provide a self-locking wear liner ring that requires no weldment around the top thereof. In the drawings:

FIG. 1 is an elevation view in cross-section of a portion of a railway car showing the wear liner or ring in position between the mating center plate of the car body bolster and the truck bolster center bowl;

FIG. 2 is a plan view of the center plate area of the bolster, showing the wear lining of FIG. 1 after being welded in position; and

FIG. 3 is an elevation view in cross-section of a portion of a railway car showing a modification of the wear ring liner.

In accordance with the present invention, there is provided a railroad car comprising a car body bolster assembly supported on a car truck bolster assembly by means of a circular body bolster center plate boss mating with a circular bowl or recess having an interior annular wall in the truck bolster. A circular wear ring is disposed within the recess in abutment with the interior wall. The interior wall contains a double taper in different directions from top to bottom and the ring contains a double tapered outer surface complementary to the interior wall.

The wear liner 10, as shown in FIGS. 1, 2 and 3 is located within the truck bolster center bowl 12. The liner is in the form of a split ring that is continuous around its circumference except for a gap 14 therein. As shown in FIG. 1, the ring has a regular cylindrical inner surface 16 and an outer surface 18 that contains a double taper from the top to the bottom. The ring is generally formed or fabricated from a wide range of alloy or carbon wear resistant steels.

The inner wall 20 of the recess is first tapered outwardly a portion of the distance from the top to the bottom and then tapered inwardly a portion of the distance. Both tapers are shown to be substantially equidistant and this is preferable. The drawings also show that the tapered surfaces meet at an obtuse angle. However, the tapered surfaces may be joined by a vertical wall portion 22 if desired.

The liner 10 is fitted within the circular recess 24 of the center bowl around the periphery thereof and is in abutment with the interior vertical wall 20 of the center bowl. This is accomplished by merely contracting the ring, placing it in the recess and allowing it to snap into position. As shown in FIG. 2, the ring is then welded at the gap 14 to the interior annular wall. When the vehicle is assembled, the vertical surface of the male body center plate boss 26 fits with the liner to protect the truck bolster center plate wall 20 from wear. Since the vertical ring forces are both up and down, the double taper fit between the ring and truck bolster rim will limit ring movement and insure control of the wear and working clearances at the car truck interface thus providing for long maintenance-free life. Owing to the construction of the ring, welding around the top could be eliminated if desired.

Having thus described the invention in detail and with sufficient particularity as to enable those skilled in the art to practice it, what is desired to have protected by Letters Patent is set forth in the following claims.

30 The embodiments of the invention in which an exclusive property or privilege is claimed are defined as follows:

1. In a railroad car comprising a car body bolster assembly supported on a car truck bolster assembly by means of a circular body bolster center plate boss mating with a circular bowl having an interior annular wall, the improvement comprising a circular wear ring disposed within said bowl in mating relation the interior wall, said interior wall having a double taper forming a 35 concave configuration being first tapered outward a portion of the distance from top to bottom and then tapered inward a portion of the distance, said ring having a gap therein and having a double tapered convex outer surface from top to bottom complementary to said interior wall and an inner surface mating with the center plate boss.

2. Car of claim 1 in which the inward and outward tapers are substantially equidistant.

3. Car of claim 1 in which the tapered surfaces meet at an obtuse angle.

4. Car of claim 1 in which the tapered surfaces are joined by a vertical wall portion.
